(57) **CLAIM**

The ornamental design for a canister as shown and described.

DESCRIPTION

FIG. 1 is a first perspective view of the design;

FIG. 2 is a front elevational view thereof;

FIG. 3 is a rear elevational view thereof;

FIG. 4 is a first side elevational view thereof;

FIG. 5 is a second side elevational view thereof;

FIG. 6 is a top plan view thereof;

FIG. 7 is a bottom plan view thereof; and,

FIG. 8 is a cross-sectional view thereof taken at section line 8-8 of FIG. 6.

The broken lines in the drawings depict portions of the article that form no part of the claimed design.

1 Claim, 8 Drawing Sheets
